CONVECTOR OR OTHER HEAT EXCHANGE DEVICE

Arthur B. Modine, Racine, Wis., assignor to Modine Manufacturing Company, Racine, Wis., a corporation of Wisconsin

Application January 13, 1951, Serial No. 205,860

3 Claims. (Cl. 257—256)

The invention relates generally to a fluid conduit for use fluid lines, or the like, and more particularly to such a conduit having ready application to a convactor, or other type of heat transfer structure. Certain features of this invention are broadly applicable to the embodiments as disclosed and claimed in my co-pending application Serial No. 205,859, filed January 13, 1951.

In connection with the transfer of fluids for heat exchange, or other purposes, the conduit oftentimes must be made of materials having special or suitable characteristics, as for example, in connection with fluids having corrosive characteristics or containing material having such characteristics, the material embodying the conduit must be constructed of a material which is not appreciably affected by the material which it is to carry. Thus while it may, for example, be desirable to form the conduit of steel for reason of strength or in order to conserve in usage of more valuable metals, the particular application to which the conduit is to be put would render it necessary to fabricate it out of a different material, as for example, brass or copper, which would considerably increase the cost of the finished structure. A typical example of such a problem is in the heat exchanger field, wherein the use of carbon steel tubing, or the like, is impractical where water or steam is flowing therethrough due to the rusting action on the tubing. Consequently, such type heat exchangers normally employ brass or copper tubing.

The present invention contemplates the production of tubing, or other fluid carrying passages, which is in the form of a bimetallic structure, the interior of the same having a liner of metal having suitable characteristics for the fluid to be carried, and the outer shell of the structure formed from a metal which may be relatively inexpensive and otherwise generally unsuitable for use in direct contact with the fluid to be carried.

Another object of the invention is to provide such a bimetallic structure which is simple in construction, durable, and easily and relatively inexpensively fabricated.

Another object of the invention is the production of such a structure which may be readily designed to form a closed passage, as for example, in use in connection with heat exchange structures, and in which case it may be readily provided with an efficient fin structure with substantially no change in the fabricating techniques required.

A further object of the invention is the production of such a structure which may be readily fabricated by the use of so-called stitch type of welding equipment.

A further object of the invention is the production of such a structure in which the heat conductive characteristics of the respective materials employed may be effectively utilized, and a fin structure produced having, in effect, characteristics corresponding to a tapered fin with its resultant high efficiency.

Many other objects and advantages of the construction

2

herein shown and described will be obvious to those skilled in the art from the disclosure herein given.

To this end my invention consists in the novel construction, arrangement, and combination of parts herein shown and described, and more particularly pointed out in the claims.

In the drawings, wherein like reference characters represent like or corresponding parts:

Fig. 1 is a side elevational view of a length of tubing constructed in accordance with the present invention;

Fig. 2 is a transverse sectional view of the tubing illustrated in Fig. 1;

Fig. 3 is a side elevational view of a fluid passage structure closed at opposite ends and provided with inlets and outlets, as well as heat transfer fins whereby the device is of particular use in a heat exchange structure;

Fig. 4 is a transverse sectional view through the structure illustrated in Fig. 3 taken approximately on the line 4—4 of Fig. 3;

Fig. 5 is a sectional view through one of the inlet or outlet fittings employed in connection with the structure illustrated in Fig. 3; and

Fig. 6 is a transverse sectional view similar to Fig. 2 of a modified form of the invention.

Referring to the drawings, and particularly Figs. 1 and 2, 1 indicates generally a tubular structure illustrated in the present embodiment of the invention as comprising a pair of strips of material 2 and 3, each of the latter being provided with similar but oppositely extending offset portions 4 and 5, with the peripheral longitudinal edges of the members 2 and 3 being provided with co-extensive flanged portions 6. Positioned between the members 2 and 3 is a liner comprising a pair of strips 7 complementary in shape to the respective members 2 and 3, whereby the offset portions 8 of the strips 7 lie in close engagement with the adjacent respective offset portions 4 and 5, and the flanged portions 9 of the strips 7 are positioned between the flanges 6 of the members 2 and 3.

20 The members 2, 3, and 7 are assembled as illustrated in Fig. 2, and suitably secured in fluid tight relation, as for example, by a line of welding 11 run along each of the flanges 6. The welding 11 may be readily performed by various means, including that of the so-called stitch type of welding equipment, wherein the welding current is intermittently applied to the structure as the assembled tubing passes therethrough. The liners 7 may thus be made of a material having suitable characteristics for engagement with the fluid to be carried, and may be

25 of very light gauge, as the outer housing will normally be designed to carry operating stresses. It will be apparent from the above that the thickness of the liners 7 need merely be sufficient to provide a desired resistance against corrosive, or other action of the fluids carried, resulting in the use of a minimum of material which normally will be relatively expensive as compared with that of the material forming the housing, with the outer housing constructed to withstand any stresses which may be involved. As the flanges 9 of the respective liners 30 are bonded together, an effective seal is provided whereby none of the fluid carried will come in contact with the metal forming the outer housing.

35 It will be apparent that as the elements forming the tubing may be readily fabricated by means of continuous rolling equipment, or the like, and bonded together by continuous operating equipment, the tubing may be very inexpensively and speedily manufactured, resulting in a finished product of relatively low cost suitable for applications normally requiring relatively expensive structures.

40 Separate lengths of tubing, such as that illustrated

in Figs. 1 and 2, may be readily and efficiently connected in series by the use of suitable connecting members or nipples constructed of metal similar to that employed for the liners 7, with the nipples extending into adjacent ends of the tubing and bonded to the inner liners 7, as well as to the outer housing.

The present invention, as previously mentioned, may be readily employed in the fabrication of closed chambers or passages, and provided with fin elements for specific application in connection with heat exchange structures, or the like, and such a structure is illustrated in Figs. 3, 4, and 5. Referring to the latter, the numeral 21 indicates generally a tubular section for use in a heat exchange structure, or the like, and comprises a pair of outer housing members 22 and 23 respectively having offset portions 24 and 25, with the members 22 having relatively wide flange portions 26, and the member 23 having relatively narrow flanges 26'. Positioned between the members 22 and 23 is a pair of liner strips 27 complementary in shape to the respective members 22 and 23, whereby the offset portions 28 of the strips 27 lie in cross engagement with the adjacent respective offset portions 24 and 25, and the flange portions 29 of the strips 27 positioned between the flanges 26 and 26' of the members 22 and 23.

Other than as to the differences in width of the flanges 26 and 26', the structure thus far described is similar to that illustrated in Figs. 1 and 2. However, as clearly illustrated in Fig. 3, the ends 31 of the offset portion 25 terminate in the plane of the flanges 26', so that the offset portion 25 is closed at either end, and the flange 26' extends completely around the offset portion forming an elongated recess. The member 22 is similarly formed with the ends of the offset portion 24 being closed in the same manner, whereby the flange 26 extends completely around the offset portion 24. The offset portions 24 and 25 are of equal length, as well as equal width, as illustrated in Fig. 4, with the side walls of the respective offset portions being uniform about the periphery of the offset. The liner members 27 are similarly constructed, whereby the offset portions 28 of the liners are co-extensive with and positioned closely adjacent to the walls of the offset portions 24 and 25 of the respective members 22 and 23, each liner member being co-extensive in length with that of the housing members 22 and 23. As illustrated in Fig. 3, the respective elements are secured together by a single continuous line of welding 32 extending completely around the offset portions, thereby forming a closed chamber completely lined with metal forming the liner 27.

In the embodiment of the invention illustrated, the heat exchange section above described is provided with a pair of ports 33 adjacent one end 31 of the device, and a second pair of ports 34 at the opposite end 31, only one of the ports 34 being illustrated. The four ports permit the connection of a plurality of sections, such as that illustrated in Fig. 3, to be connected in parallel, with the ports 33, for example, forming an inlet to the respective section, and the ports 34 forming the outlet thereof, or vice versa. All of the inlet and outlet connections are similarly constructed, Fig. 5 disclosing a sectional view through one of the ports 34. In the embodiment of the invention illustrated, the ports 33 and 34 on the members 22 and 23 are each formed by an outwardly flared opening 35 in which is positioned a suitable sleeve 36, or the like, constructed of the same or a similar metal to that forming the liner 27 and suitable for use in the particular application involved, and having an external flange 37 at its inner end bearing against the adjacent liner 27, the latter likewise having an opening 38 therein aligned with the opening 35 for the reception of the sleeve 36. As clearly shown in Fig. 5, the material of the liner 27 adjacent the opening 38 is drawn or flared outwardly, corresponding with the shape of the opening 35. The sleeve 36 is secured to the liner 27 and outer housing 28

5 by suitable means, as for example, bonding material 39 which rigidly secures the sleeve to the outer housing and, at the same time, provides an effective seal between the sleeve and the liner 27, thereby preventing any fluid in the structure from coming in contact with the metal of the outer housing.

In assembling the structure, liners 27 are positioned in their respective outer housings, and the sleeves 36 inserted in the respective ports, and the sleeves may then be suitably bonded to the adjacent structure. This may be accomplished by placing a small ring of bonding material around the sleeve adjacent the flange 37, and another ring of bonding material adjacent the external juncture of the flared portion 35 of the outer housing and the external surface of the sleeve, whereupon by the application of heat, the bonding material will fill up any voids between the sleeve and adjacent structure, and effectively bond the same together, following which the elements may be stitch welded together, as illustrated.

20 Referring to Fig. 4, it will be noted that the flanges 26 and 26' of the respective housing members and the flanges 29 of the liners 27, in effect, form a composite heat transfer fin. Assuming the structure of Fig. 4 is intended for use as a heat exchanger in a hot water system, or the like, the outer housing may be of steel, and the inner liners of copper or brass, with the sleeves 36 likewise of brass, in which case the liners which are directly in contact with the fluid in the exchanger section would be of relatively high heat conductivity, whereas 25 the outer housing, which would be of relatively low heat conductivity, will not be in direct contact with the fluid in the device. It will be noted that the fin structure thus formed immediately adjacent the chamber formed by the offset portions is of four thicknesses of material, the two 30 inner thicknesses comprising the material of high heat conductivity directly in contact with the fluid, and the outer thickness of lower heat conductivity. Thus, at such sections of the fins maximum transmission of heat results. For a distance beyond the edges of the flanges 29 to the 35 outer edge of the flanges 26', a double thickness of the outer housing is provided to achieve an intermediate amount of heat dissipation, with the extremely outer ends of the fin structure formed by the outer portions of the flanges 26 providing a single thickness of material for 40 heat transmission and dissipation.

45 It will be apparent that this construction provides a fin structure of varying thicknesses so that the heat conductivity and dissipation diminishes towards the outer edge of the fin in a manner similar to that of a tapered fin, which is recognized to be of high efficiency in the 50 conduction of heat for heat transfer purposes. Likewise, the inherent heat transfer characteristics of the fin resulting from the material employed therein is such that greater conductivity is achieved adjacent the fluid chamber 55 and diminishing outwardly therefrom, generally in proportion to the amount of heat to be dissipated by the various portions of the fin. It will be noted that the present invention is therefore particularly adapted to heat 60 exchanger surface enabling not only the production of a simple, inexpensive structure, but one having a high degree of efficiency for the purposes intended.

65 Illustrated in Fig. 6 is a modified form of the structure illustrated in Figs. 1 and 2, and disclosing the application of the present invention to a fluid conducting tube 70 comprising an outer housing 41 formed from a single sheet of material in combination with a liner 42, likewise formed from a single sheet of material. In this construction the longitudinal edges of the material forming the housing are provided with generally radially positioned, longitudinally extending flanges 43, between which are positioned similar flanges 44 formed in the longitudinal edges of the liner strip 42. The flanges 43 and 75 44 are secured together by a line of welding 45 which, as in the case of the previous structure, may take the form

of stitch welding, or the like, thereby forming a bimetallic fluid conduit.

It will be apparent that while I have illustrated the liners in the constructions of Figs. 1 and 3 as formed of individually separate strips, the liners 7 or 27 could be formed from a single strip of double width folded along a pair of corresponding edges, so that actually only one of the seams in the line of welding forms a seal for the chamber or tube thus formed. The same is also true of the outer housing, but for simplicity in manufacture and fabrication of the structure, it is preferred to make the same as illustrated in the drawings. Likewise, while I have shown both housing members provided with offset portions, if desired, only one offset could be provided with the other housing member of planar construction.

It will be apparent from the above description that I have provided a novel, bimetallic conduit having wide application in various fields, and of particular advantage in connection with heat exchange structures, which is relatively simple in construction, may be inexpensively manufactured, and which provides high efficiency in heat transfer applications.

Having thus described my invention, it is obvious that various immaterial modifications may be made in the same without departing from the spirit of my invention; hence, I do not wish to be understood as limiting myself to the exact form, construction, arrangement, and combination of parts herein shown and described or uses mentioned.

What I claim as new and desire to secure by Letters Patent is:

1. In a finned fluid conduit for use in a heat transfer structure, the combination of an outer housing structure formed from ferrous sheet material and comprising a pair of longitudinally extending sections, one of which is provided with a longitudinally extending offset portion therein, an inner separate liner structure formed from non-ferrous sheet material and comprising a pair of sections complementary to the interior surfaces of the housing sections, said housing sections having continuously extending, peripheral mating flanges, one of said pair of mating flanges of lesser width, said liner sections having similar continuously extending, complementary mating flanges positioned between corresponding mating flanges of the housing section and forming a fluid conduit when affixed together in fluid-tight relationship and also providing substantially simulated tapered fins, means for securing together in fluid-tight relationship mating flanges of the liner sections and the latter to adjacent flanges of the housing sections to form a closed chamber, said means for securing comprising a welded connection between the flanges of the liner and housing sections, said housing

and liner structures each having a pair of longitudinally spaced and aligned openings therein, the openings in the separate liner structure being axially aligned with the openings of the housing structure, said openings communicating with said chamber and forming inlet and outlet ports therefor, and separate sleeve connections positioned in their respective openings and secured in fluid-tight relationship to said liner structure, and said separate sleeve connections extending normally outwardly with respect to the longitudinally extending sections of the finned fluid conduit.

2. In a finned fluid conduit for use in a heat transfer structure as set forth in claim 1, wherein the aforesaid openings of said housing are formed with outwardly extending flanges, each of said sleeve connections extending normally outwardly and formed with an annular flange, and each of said annular flanges affixed to the contiguous portion of the liner about the opening therein through which the respective sleeve extends in fluid-tight relationship, and the outer end of each of the flanged openings of the housings affixed in fluid-tight relationship to the contiguous portion of the respective sleeves mounted therein.

3. In a finned fluid conduit for use in a heat transfer structure as set forth in claim 1, said complementary mating flanges of the liner sections being of lesser width than the least of said mating flanges of said housing sections, whereby simulated tapered fins are provided on the closed chamber of the finned fluid conduit.
